CLAIM

The ornamental design for a kitchen appliance with two-dimensional applied surface graphic, as shown and described.

DESCRIPTION

The file of this patent contains at least one drawing executed in color. Copies of this patent with color drawings will be provided by the Office upon request and payment of the necessary fee.

FIG. 1 is a front perspective view of a kitchen appliance with two-dimensional applied surface graphic according to our design; and,

FIG. 2 is a front elevation view thereof.

The portions of the article shown in broken line form no part of the claimed design.

Dash-dot lines adjacent un-shaded areas represent bounds of the claimed design and form no part of the claimed design themselves.
